VERNER J. WAHLSTROM, OF BROOKLYN, NEW YORK, ASSIGNOR TO WAHLSTROM TOOL COMPANY, OF NEW YORK, N. Y., A CORPORATION OF NEW YORK.

CHUCK.

1,162,197.

Specification of Letters Patent.

Patented Nov. 30, 1915.

Application filed December 22, 1914. Serial No. 878,477.

To all whom it may concern:

Be it known that I, VERNER J. WAHLSTROM, a citizen of the United States, residing at Brooklyn, county of Kings, and State of New York, have invented a new and useful Improvement in Chucks, of which the following is a specification.

This invention relates to an improvement in chucks and has for its object the production of a simple device for clamping tool shanks within a wide range of shank sizes; and the invention consists in certain parts, constructions and combinations which will be hereinafter fully described and then specifically pointed out in the claims hereunto appended.

In the accompanying drawings, which form a part of this specification and in which like characters of reference indicate the same or like parts, Figure 1 is a sectional view of a device constructed in accordance with the invention; Figs. 2 and 3 are cross-sectional views taken on the line 2—2 in Fig. 1 showing the parts in different positions; Figs. 4 and 5 are fragmentary detail cross-sectional views also taken on the line 2—2 in Fig. 1; Fig. 6 is a detail view of one of the clamping jaws; and Fig. 7 is an end view of the structure shown in Fig. 6. The device selected to illustrate the invention is but one of many possible concrete embodiments thereof, and the invention therefore is not to be restricted to the precise details of the structure shown and described but is only to be limited by the scope of the appended claims.

Referring to the drawings, 1 indicates a tapered shank, the upper part of which is broken away but is adapted to be used in connection with a drill press or other machine tool. The shank 1 is connected by means of a pin 2 to a chuck body 3 having radial slots 4 cut therein. Surrounding the body 3 is a sleeve 5 of a well-known construction having a plurality of cam surfaces 6 adapted to coöperate with jaws to be hereinafter described. The sleeve 5 is secured to an upper plate 7 and a lower plate 8, both of which are journaled upon the body 3 before referred to. Within the sleeve and surrounding the body 3 is a torsion spring 9, one end of which is secured to the body and the other end to the plate 7 in a manner well known in the art and clearly disclosed in my earlier Patents Nos.

996,953, 996,954, 996,955, 1,026,187 and 1,046,237.

Located within the slots 4 are a plurality of clamping jaws all alike. Each of these jaws has two integral segmental sections 10 marked 10 and 11 of different radii, arranged to form an unbroken clamping surface, the radial centers of the section being spaced apart, as clearly indicated in Fig. 7 by means of the arrows 12 and 13. At one end of the section having the smaller radius there is formed a reentrant angular recess 14, the purpose of which will be hereinafter described. Each jaw is provided with segmental ledges 15, one at each end of the section having the greater radius.

The body 3 is provided with a series of transverse slots 16 opening into the radial slots 4 before referred to, and in these transverse slots 16 are located the coils of torsion springs 17. One end of each of these springs is pocketed in a suitable aperture 18 drilled in the body 3. The free end of each spring 17 engages one of the ledges 15 before referred to. To provide clearance for the extreme end of each spring 17 there is cut in the sleeve 5 a series of internal circumferential channels 19.

Fig. 3 illustrates the parts in their normal position. Assuming that the device is in use on a drill press which is running and it is desired to introduce a tool shank between the clamping jaws, the sleeve 5 is grasped by the operator and stopped. This action sets up a relative rotary movement of the chuck body, and the sleeve 5 and the springs 17 then come into action to throw the clamping jaws 10—11 radially outward as they travel down the cam surfaces 6 of the sleeve. By reference to Fig. 2, it will be seen that the reentrant angular recesses 14 of the clamping jaws 10—11 permit the jaws to be thrown outwardly to the extreme limit of their outward movement and close into the corners formed between adjacent cam surfaces. It will be noted, too, that the springs, bearing as they do upon two points of the segmental ledges 15, keep the clamping jaws in their normal position as they move outwardly. The tool shank having been inserted between the jaws and the sleeve 5 released, the spring 9 produces a relative rotary movement between the body and sleeve in the reverse direction, and the jaws are forced inward to the tool shank 110.

by the cam surfaces 6. As soon as the jaws bite the tool shank and the resistance of work is thrown upon the tool, the jaws rock, rolling up the cam surfaces and firmly 5 clamping the tool shank, this action being due to the action of the two segmental sections of different radii. In the event of a tool clamped in the device becoming wedged or jammed in the work for any reason, its 10 shank will ride off from the clamping surfaces of the jaws 10—11 into the reentrant angular recesses 14, as shown in Fig. 5, the result being that neither the tool shank nor the jaws will be damaged in this emergency. 15 When the tool is to be released from the chuck, the sleeve 5 is again grasped and stopped which permits the springs, at this time bearing only upon one point of the 20 ledges as shown in Fig. 4, to move the jaws again outwardly and at the same time to turn them back to their normal position or that shown in Figs. 2 and 3.

What is claimed is:

- 25 1. In a chuck, a cam actuated rolling jaw having two integral segmental sections of different radii.
2. In a chuck, a cam actuated rolling jaw having two integral segmental sections of different radii arranged to form an unbroken clamping surface.
3. In a chuck, a cam actuated rolling jaw having two integral segmental sections of different radii arranged to form an unbroken clamping surface at one end of the 35 section having the smaller radius and having a reentrant angular recess at the other end of the same section.
4. In a chuck, a rocking jaw having two integral segmental sections of different radii and two integral projecting ledges one at either end.
5. In a chuck, a rocking jaw having two integral segmental sections of different radii and having two integral projecting ledges one at either end of the section having the greater radius.
6. In a chuck, a cam actuated rolling jaw having two integral segmental sections of different radii and being of a length exceeding the sum of the radii.
- 50 7. In a chuck, a cam actuated rolling jaw having two integral segmental sections of different radii the radial centers of the sections being spaced apart.
8. In a chuck, a cam actuated rolling jaw having two integral segmental sections of different radii the radial centers of the two sections being spaced apart to cause the adjacent surfaces of the two sections to form 60 an unbroken clamping surface.

9. In a chuck, the combination with a body having radial slots, of cam actuated rolling jaws having two integral segmental sections of different radii located within the slots, and springs carried by the body and 65 engaging the jaws one at each end of each jaw for normally moving said jaws radially outward.

10. In a chuck, the combination with a body having radial slots and transverse 70 slots opening into said radial slots, of clamping jaws located in the radial slots, and springs having torsion coils located in the transverse slots of the body and projecting ends one end of each spring engaging 75 a suitable aperture in the body and the other engaging one end of one of the clamping jaws.

11. In a chuck, the combination with a body having radial slots, of clamping jaws 80 located in said slots each jaw having a projecting ledge at each end, and springs carried by the body each having projecting ends engaging one of the ledges.

12. In a chuck, the combination with a 85 body having radial slots, of clamping jaws located in said slots each jaw having a projecting ledge at each end said ledge being segmental in shape, and springs carried by the body each having a projecting end 90 engaging one of the segmental ledges and adapted to move said jaw radially outward and turn it in transit to normal position.

13. In a chuck, the combination with a body having radial slots, of rocking clamping 95 jaws located in said slots, springs carried by the body and each having a projecting end engaging one of the jaws, and a sleeve surrounding the body and having an internal circumferential channel cut there-in to provide clearance for the free end of 100 the spring.

14. In a chuck, the combination with a body having radial slots, of rocking clamping jaws located in said slots each jaw having a projecting ledge at each end, a plurality of springs carried by the body each having a projecting end engaging one of the jaw ledges, and a sleeve surrounding the body having a plurality of internal circumferential channels to provide clearance for 110 the ends of the springs.

In testimony whereof, I have signed my name to this specification in the presence of two subscribing witnesses.
